(57) **CLAIM**

The ornamental design for a curved sofa table with two-level top, as shown and described.

DESCRIPTION

FIG. 1 is a front perspective view of a sofa table showing my design.

FIG. 2 is a front elevational view thereof.

FIG. 3 is a top plan view thereof.

FIG. 4 is a left side elevational view thereof.

FIG. 5 is a rear elevational view thereof.

FIG. 6 is rear elevational view thereof; and,

FIG. 7 is a bottom view thereof.

Elements shown in broken line do not form part of the claimed design.
